F. E. Pitts,

Grate.

No. 16,768.

Patented Mar. 3, 1857.

Henry Baldwin Jr. (Witness) F. E. Pitts

UNITED STATES PATENT OFFICE.

FOUNTAIN E. PITTS, OF NASHVILLE, TENNESSEE.

BACK PLATE FOR FIREPLACES AND GRATES.

Specification of Letters Patent No. 16,768, dated March 3, 1857.

To all whom it may concern:

Be it known that I, FOUNTAIN E. PITTS, of Nashville, in the county of Davidson and State of Tennessee, have invented a new and 5 useful Back Plate for Fireplaces and Grates, of which the following is a full, clear, and exact description, reference being had to the accompanying drawings, which make part of this specification, and in which—
10 Figure 1 represents a view in perspective of my improved back plate. Fig. 2, represents a section through the same at the line $\alpha\alpha$ of Fig. 1, and Fig. 3, represents a section at the line $\alpha\alpha$ of Fig. 1.

15 My invention consists in arranging a grating, the bars of which are angular, in the throat of a chimney in such manner as to cause the smoke to pass through it, the peculiar form and arrangement of the bars being such as to arrest much of the heat, that would otherwise pass up the chimney, and radiate it into the room. This grating may 20 be made of either wrought or cast-metal, but I prefer to make it of cast-iron, and of not less than an inch and a half in thickness, and it may be made with lugs to rest on the sides of the chimney. This grating should 25 be so placed that it will incline forward at an angle of about 45° ; but it should rest on the lugs in such manner that it can turn on them, as on trunnions, to be thrown back, when necessary, for the purpose of cleaning the chimney, regulating the draft, etc. The 30 bars of this grating are of uniform width and depth with parallel sides and flat backs, while the face of each of them is an angular ridge, formed by the junction of two planes at an angle of about 90° . The sides of the bar are perpendicular to its back; and the 35 bars are so placed as to leave oblong spaces between their adjacent sides equal to about one-quarter of the width of the back of the bars except at each end, where they are joined. The face of the grating, thus constructed, 40 consists of a series of angular ridges and furrows, with a slot in the bottom of each furrow. This form and arrangement of the bars is such as to secure the most effectual interception of the heat at the entrance of the chimney, consistently with the

most effectual radiation of that intercepted heat into the room. The broad converging surfaces of the grate-bars, over which the smoke has to pass before it can enter the chimney through the narrow slots, operates 55 to strain, as it were, the heat out of the smoke.

The area of the face of the grate is greatly increased by the ridges, yet, nevertheless, it occupies a position relative to the fire-place, 60 and to the room, highly favorable to the radiation of the heat into the lower part of the room, where it is most required. The elongated openings between the bars also operate advantageously in distributing the smoke 65 equally, over the whole surface of the bars, in its passage through the grating. These openings should equal about one-fifth of the area of the flue. This back plate will also perform the functions of a damper to regulate 70 the draft, by varying the area of the opening of the throat. It is obvious that it can readily be adapted and applied to any form of chimney.

I am aware that grated, reticulated and 75 perforated plates (the last being described in the patent granted to Jacob Cohen April 15th, 1850) have heretofore been used in the throats of fire-places or flues of stoves; also, that a fire-back, composed of metallic plates, 80 arranged like the slats of a window-blind, is described in the patent, for a cooking-stove, granted to G. Smith and H. Brown May 15th, 1847. I claim none of these. I am also aware that it has been proposed to 85 place a grate, with angular bars similar to mine, in the flues of cooking ranges. I do not claim the plate so placed. But

What I do claim as my invention and desire to secure by Letters Patent, is—
90

The back-plate for fire-places and grates, constructed with the series of angular ridges, furrows, and slots, in the manner and for the purposes herein described.

In testimony whereof, I have hereunto 95 subscribed my name.

FOUNTAIN E. PITTS.

In presence of—

HENRY BALDWIN, Jr.,
A. E. H. JOHNSON.
